UNITED STATES PATENT OFFICE.

WILLIAM A. BRADEN AND JAMES B. SMALLEY, OF CHICAGO, ILLINOIS, AS
SIGNORS TO THE ELEVATOR SUPPLY & REPAIR COMPANY, OF CHICAGO,
ILLINOIS, A CORPORATION.

DOOR-OPERATING MECHANISM.

SPECIFICATION forming part of Letters Patent No. 700,404, dated May 20, 1902.

Application filed November 6, 1899. Serial No. 735,888. (No model.)

To all whom it may concern:

Be it known that we, WILLIAM A. BRADEN and JAMES B. SMALLEY, residents of Chicago, county of Cook, and State of Illinois, have invented certain new and useful Improvements in Door-Operating Mechanism, of which the following is a full, clear, and exact description.

The present invention has for its object to provide improved door-operating mechanism more particularly designed for the opening and closing of the doors of elevator-hatchways.

The invention relates more particularly to that class of door-operating mechanism in which compressed air or other fluid under pressure is employed as the motive power.

The invention consists in various novel features of improvement hereinafter described, illustrated in the accompanying drawings, and particularly pointed out in the claims at the end of this specification.

Figure 1 is a view in central vertical section through a door-operating mechanism embodying our invention, parts being shown in elevation. Fig. 2 is a view in end elevation looking from right to left of Fig. 1. Fig. 3 is a view in end elevation looking from left to right of Fig. 1. Fig. 4 is a view in vertical cross-section through the upper part of the right-hand block or casing, the section being taken on line 4 4 of Fig. 1. Fig. 4^a is a detail view in cross-section of the valve shown in Fig. 6. Fig. 4^b is a plan view of the trigger and connected parts. Fig. 5 is an enlarged fractional view, in vertical section, through the right-hand end of the mechanism, the section being taken upon line 5 5 of Fig. 4. Fig. 6 is a view similar to Fig. 5, but is taken upon line 6 6 of Fig. 2. Fig. 7 is a detail plan view of the valve-seat. Fig. 8 is a view in central vertical section through the left-hand end of the apparatus shown in Fig. 1. Fig. 9 is a view in vertical cross-section on line 9 9 of Fig. 8. Fig. 10 is a view in vertical section on line 10 10 of Fig. 9. Fig. 11 is a view in vertical section on line 11 11 of Fig. 9. Fig. 12 is a diagrammatic view illustrating one way in which our improved door-operating mech-

anism may be applied to elevator-hatchway doors.

Our improved door-operating mechanism is shown as mounted upon a supporting-bar A, which bar will be fixed at some convenient point above or adjacent the top of the door of the elevator-hatchway.

In Fig. 12, A' indicates the elevator-well, A² the elevator-car, and B' the sliding elevator-hatchway door.

The door is operated through the medium of a lever B², pivoted at its upper end to the hatchway-wall and having a slotted lower end engaging a pin B³ upon the door B'. A bar B (see Fig. 1) is pivotally connected to the lever B² near its upper end and is pivotally connected at its opposite end, as at b', to the head-block 6. These door-operating connections are merely illustrative to complete the disclosure of the invention, and it will be understood that the improved door-operating device below described and claimed may be applied to various kinds of doors and with various forms of connecting-levers. Upon the bar A are mounted the end blocks or casings C and D, these blocks or casings being shown as held in position upon the bar A by the screws 2 and 3. To the lower end of the block or casing C is removably and exteriorly secured in any suitable manner—for example, by screw-bolts C², (see Fig. 5,)—the valve seat or base C'. The upper part of the block C is formed with a screw-threaded offset c, to which is connected one of the threaded ends of the cylinder E. In like manner the block or casing D is preferably formed with a threaded offset d, to which is connected the corresponding threaded end of the cylinder F. The cylinders E and F are oppositely arranged, as shown in Fig. 1, and in the cylinder E is located the piston G, that is fixed to the hollow piston-rod 4. The piston G is furnished with a cup-leather g, held in place by the usual washer g'. In like manner the cylinder F carries a piston G', having a cup-leather g², held in place by the disk or washer g³, the piston G' being attached to the hollow piston-rod 5. The inner ends of both the piston-rods 4 and 5 are shown as con-

nected to a head-block 6, the yoke-shaped arm 7 of which spans the transverse tubular rod H. The screw-threaded ends of the rods H have caps 8 and 9 attached thereto, the sides of these caps having screw-threaded holes therein to receive the screws 10 and 11, that pass through the laterally-projecting flanges c^2 and d^2 , formed, respectively, at the upper ends of the blocks or casings C and D.

10 In the block or casing C is formed an admission-port 15 and a discharge-port 16, (see Fig. 2,) these ports being connected with suitable air (or like fluid) admission or discharge pipes. (Not shown.) The admission-port 15 is connected by a channel 15^a with a valve-chamber 17, within which chamber is located the slide-valve K, the under surface of which is formed with the usual exhaust-cavity k. In the removable valve seat or plate C' (see Figs. 5 to 7) is formed a central exhaust-channel 18, that connects with the exhaust-port 16, opening outwardly at the end of the block or casing C. Through the valve-seat C' is also formed a channel 20, that extends downward, (see Fig. 6,) thence diagonally across the base of the seat, (see Fig. 7,) and thence upward (see Figs. 4 and 6) through the block or casing C to a point opposite the open end of the tubular rod H, and by this channel 20 air or like fluid under pressure will be admitted to and discharged from the cylinder F in manner to be presently explained. In the valve-seat C' is also formed a channel 22, that leads downwardly from the base of the valve-seat, (see Fig. 6,) thence outwardly, (see Fig. 7,) and thence upwardly (see Fig. 5) to a chamber 23, within which is placed a ball-valve 24, that seats over the top of the channel 22. By having the valve-seat C' movably secured to the exterior of the casing C ready access is afforded to these ports and passages. From the chamber 23 a channel 25 leads to the cylinder E. The top of the chamber 23 is shown as closed by a screw-threaded plug 26, this construction serving to permit the channel 22 to be readily drilled. A throttling or snifting needle-valve M intersects the channel 22 and obstructs more or less a small transverse channel 28, that leads from the cylinder E to the channel 22. (See Fig. 5.) The threaded portion of the needle-valve M passes through an adjustable stuffing-box m, and by the adjustment of the needle-valve M the discharge of air from the cylinder E to the channel 28 can be accurately regulated. The channel 22 is connected by a cross-channel 29 (see Fig. 4) with an annular chamber 29^a, that encircles the chambered plug P, that passes through the block or casing C (see Fig. 6) and into the cylinder E, the outer end of the plug P being preferably of polygonal shape to permit it to be conveniently engaged by a wrench. The interior of the plug P is connected by holes p with the annular chamber 29^a, and the inner end of the plug P is open. The inner end of the plug is fitted with packing-rings p^3 and washer p^3 to retain

said rings in place upon the plug, and through the end of the plug is passed a wire p^3 to prevent the accidental slipping of the rings and washers from the end of the plug in case they should become loose.

In the block or casing D is formed the vertical channel 30, (see Figs. 8 and 11,) that connects the tubular rod H with the annular space 31, that extends around the screw-threaded hollow plug P', that passes through the casing D and through the end of the cylinder F. From the annular space or channel 31 leads a channel 32, (see Fig. 11,) from which a channel 33 (see Fig. 10) leads into the cylinder F, and the channel 32 is connected by a port 34 with a chamber 35, in which is located a ball-valve 36, that seats against the top of the port 34. The upper end of the chamber 35 is closed by a threaded plug 37, and a similar plug 38 closes the outer end of the channel 32. The chamber 35 is connected by a channel 39 with the cylinder F. The hollow plug P' is provided with ports 40, that connect the interior of the plug with the annular chamber 31, and the inner end of the plug P' is open, being merely intersected by a wire 41, that serves to prevent the packing-rings 42 and washers 43 slipping off the end of the plug in case they should become loose. A port 44 is shown adjacent the inner end of the plug P', but this is not essential where the end of the plug is open, as shown. The outer end of the plug P' is preferably formed with a polygonal portion adapted to receive a wrench by which the plug can be conveniently turned. By reference to Fig. 10 it will be seen that a needle-valve M² is arranged opposite the outer end of the exhaust-channel 33, the adjustment of this valve M² being effected by its threaded portion that passes through a corresponding threaded stuffing-box m².

From the construction of parts as thus far defined it will be seen that air under pressure being supplied to the admission-port 15 will pass by the port 15^a to the valve-chamber 17. Now when the slide-valve K is in the position seen in Fig. 6 and the pistons G and G' are in the position shown in the several views of the drawings air will pass from the valve-chamber 17 by channel 20 into the tubular rod or pipe H, thence across the channel 30, (see Fig. 11,) thence through annular chamber 31, channel 32, port 34, chamber 35, (lifting valve 36,) channel 39 to cylinder F, thereby holding the piston G' in the position shown. At such time all air will have been exhausted from the cylinder E, and the door of the elevator-hatchway may be assumed to be in closed position. If now it is desired to open the door, the slide-valve K will be shifted (by the mechanism to be hereinafter described) from the position shown in Fig. 6 until this valve K spans the ports 18 and 20, leaving the port 22 exposed. Air will then pass from valve-chamber 17 through channel 22, lifting ball-valve 24, (shown in

Fig. 5,) and through channel 25 into the cylinder E. The pistons G G' will then be moved in the direction of the arrow, Fig. 1, and at such time the exhaust from the cylinder F will occur as follows, viz: As the piston G begins to move the exhaust from cylinder F will occur through the hollow plug P', the air passing thence by ports 40, channel 30, tubular rod H, and channel 20 into the exhaust cavity k of the slide-valve K, (which at such time will span the channels 18 and 20,) thence by channel 18 to exhaust-port 16. So long as the exhaust of air through the cylinder F occurs through the plug P', such exhaust will be very rapid; but as the piston G' moves outward the plug P' will pass into the hollow piston-stem 5 and the end of the plug P' will thereby be closed, shutting off the exhaust from cylinder F through the plug P'. The exhaust from cylinder F will still continue, however, through channel 33, (see Figs. 10 and 11,) channel 32, annular chamber 31, channel 30 of tubular rod H, channel 20, exhaust-cavity k of valve K, and exhaust-channel 18. At such time, however—that is to say, during the final outward movement of the piston G'—the ball-valve 36 will close the port 34 (see Fig. 10) and will prevent the exhaust of air through the channel 39. Inasmuch as the channel 33 is controlled by the needle-valve M² it is manifest that the exhaust of air from the cylinder F can be regulated with exactness, so as to prevent all slamming of the door. If it be assumed that the door has been opened by the movement of the pistons G and G' from the position shown in Fig. 1 to the opposite ends of their respective cylinders, it being also assumed that the slide-valve K has been shifted from the position shown in Fig. 6, so as to span the channels 18 and 20, and it be now desired to restore the pistons G G' to the position seen in Fig. 1 in order to close the door, the slide-valve K will be returned (by mechanism to be presently described) to the position shown by full lines in Fig. 6, when air will pass from valve-chamber 17 by channel 20, tubular cross-rod II, channel 30, annular chamber 31, (see Figs. 10 and 11,) channel 32, port 34, chamber 35, and channel 39 to cylinder F. At the same time air will exhaust from the cylinder E at first through the plug P into annular chamber 29, through channel 29 into port 22, into cavity k of slide-valve K, and thence by exhaust-channel 18 to exhaust-port 16. As soon, however, as the piston G, when moving in direction opposite to the direction of the arrow, Figs. 1 and 5, causes the plug P to be closed by the tubular piston-stem 4 the exhaust through the plug P will be cut off and the escape of air from cylinder E will then occur through channel 28, around the end of needle-valve M, through channel 22, exhaust-cavity k of slide-valve K, and exhaust-channel 18 to exhaust-port 16. The throttling-valve M will enable the exhaust of air to be accurately regulated, so that a quick and easy move-

ment of the piston without slamming shall occur.

Blocks or casings C and D are provided, 70 as shown, at their lower ends with flat bearing-faces on both sides, so that either face may be placed against the flat supporting-bar A in securing the blocks or casings to said bar. It is possible, therefore, to remove the 75 entire structure from the supporting-bar A by removing the securing-bolts 2 and 3, which hold the blocks of casings C and D in place. The entire structure may then be shifted end for end and secured upon the bar A, so as to 80 operate in the reverse direction. The supporting-lugs a⁶ may be secured upon the bar A in any desired position. In this way the door to be shifted may be moved either to the right or to the left. The same object may be obtained by interchanging the removable valve-seat C', so that the compressed air will flow through the ports in the reverse direction.

The preferred mechanism for shifting the slide-valve K is that shown in Figs. 1 and 6 90 of the drawings. Upon the supporting-bar A are mounted the brackets a⁴ and a⁵, through which passes the valve-rod R, the rod being held in position upon the brackets or bearings a⁴ and a⁵, preferably by the retaining 95 plates or caps a⁶, secured to the brackets. Upon the valve-rod R are mounted the adjustable stops r r', that determine the throw of the rod R. A trigger S will also be mounted upon the valve-rod R, the rod R passing 100 through the trigger, which is held on the rod by the set-screw s. In order to more securely hold the trigger in position, it is preferably formed with an arm S', extending inwardly therefrom, this arm being guided by bearing 105 a⁵, through which the rod R passes, the bearing S² being fixed to the rod by a set-screw s². The trigger S, as seen in Figs. 2 and 3, projects outwardly some distance from the supporting-plate A, and this trigger is adapted 110 to be struck by a suitable shifter S², (see Fig. 12,) which is preferably vertically disposed and provided with cam-shaped ends and may be mounted upon a suitable cross-head S⁴, arranged to slide in a groove in the top of the ear A². The cross-head is controlled by the ear-operator through the medium of a pull S⁵ and an intermediate spring-held bell-crank S⁶. It will be understood that the shifter S² and its operating means for tripping the trigger S as herein set forth are merely illustrative, and any one of a number of various devices may be employed for the same purpose.

By reference to Figs. 1, 5, and 6 of the 125 drawings it will be seen that the valve-rod R passes through to the end of a cylinder T and carries a cup-leather or piston t, that is held in place by a threaded nut or washer t' against the outer end of the circular portion R' of 130 the valve-rod. This circular portion R' of the valve-rod is formed with a notch or cut-away space r², within which fits the top of the valve K, the part R' of the rod being thus

locked to the valve K. A leak port or channel t^2 connects the interior of the cylinder T with the valve-chamber 17, so that the pressure of air is at all times within the cylinder T and upon the cup-leather or piston t, tending to force it outward. Hence it will be seen that when the slide-valve K is in position shown in Fig. 6, at which time the elevator-hatchway door will be closed, the pressure of air in the cylinder T and upon the cup-leather or piston t will hold the valve K against displacement. So, also, after the trigger S has been shifted by the contact device upon the elevator-car the air within the cylinder T will be temporarily forced back into valve-chamber 17; but as soon as the contact device in the elevator is disengaged from the trigger S the pressure of air within the cylinder T will force the piston t outward, thereby automatically shifting the slide-valve K and causing the passage of compressed air to the cylinder E in order to close the door. The employment of a supplemental cylinder T and a piston for shifting the slide-valve K avoids the use of springs for this purpose and the use of a cup-leather t renders the provision of a stuffing-box for the valve-rod R unnecessary.

This invention will be found of especial advantage, because of the simplicity and effectiveness of the means whereby the slamming of the door when shifted from open to closed position, and vice versa, is prevented. A further advantage of the invention is that the parts are readily interchangeable, so as to facilitate closing a door either from right to left, or vice versa. By providing means for automatically returning the trigger to the position seen in Fig. 6, which is the normal position of the trigger when the door is closed, it will be seen that all springs for this purpose are avoided and the necessity of using a stuffing-box for the cylinder T does not exist. So, also, the arrangement of the cylinders E and F as shown not only materially simplifies the structure, but by employing cup-leathers for the pistons G G' the necessity of using stuffing-boxes for the piston-rods is avoided. In many other respects also our invention will be found to possess advantages over other door-operating devices.

It is manifest that without departing from the spirit of the invention the apparatus above described may be modified by the skilled mechanic, and it will be understood also that while the invention is more particularly designed as a means for opening and closing doors of elevator-hatchways it may be used for other purposes. Thus, for example, while in the preferred form of the invention the cylinders E and F are formed entirely separate it is manifest that a single cylinder having pistons in its opposite ends (having means between them for connection with the door) might be employed; but this would be nothing more than our two cylinders connected together.

Having thus described our invention, what we claim as new, and desire to secure by Letters Patent, is—

1. In apparatus of the character described, the combination of two oppositely-arranged, open-ended cylinders, pistons within said cylinders rigidly connected together by a common piston-rod, an operating connection for a door or device to be shifted, secured at one end to said piston-rod intermediate said pistons, and a valve common to both of said cylinders for controlling the alternate admission of fluid under pressure thereto. 80

2. In apparatus of the character described, the combination of two oppositely-arranged, open-ended cylinders, pistons within said cylinders rigidly connected together by a common piston-rod, an operating connection for a door or device to be shifted, secured at one end to said piston-rod intermediate said pistons, an admission and exhaust channel for each of said cylinders and a valve common to both cylinders for controlling the alternate admission and exhaust of fluid under pressure through said channels. 85

3. In apparatus of the character described, the combination with a suitable part, such for example as a cross-head, adapted to be connected with the door or device to be shifted, of oppositely-arranged pistons connected to said part or cross-head, cylinders wherein said pistons are contained, suitable casings at the ends of said cylinders provided with admission and exhaust channels and a hollow rod extending between said casings, substantially as described. 95

4. In apparatus of the character described, the combination with a suitable part, such for example as a cross-head, adapted to be connected with the door or device to be shifted, of pistons connected to said part or cross-head, cylinders wherein said pistons are contained, suitable channels for delivering fluid under pressure to said cylinders, escape-channels for exhausting fluid from said cylinders and adjustable throttling-valves for regulating the flow through said exhaust-channels. 105

5. In apparatus of the character described, the combination of two oppositely-arranged, open-ended cylinders, pistons within said cylinders rigidly connected together by a common piston-rod, an operating connection for a door or device to be shifted, secured at one end to said piston-rod intermediate said pistons, the outer ends of said cylinders being provided with ports for the admission and exhaust of fluid under pressure, a valve-chamber having inlet and exhaust passages, channels leading from said valve-chamber to the ports of each of said cylinders, and a valve in said chamber for controlling the flow of fluid under pressure through the said channels. 115

6. In apparatus of the character described, the combination with a suitable part, such for example as a cross-head, adapted to be connected with the door or device to be shifted,

of pistons connected to said part or cross-head, cylinders wherein said pistons are contained, admission and exhaust channels for delivering fluid under pressure to said cylinders, 5 hollow piston-rods whereby said pistons are carried, hollow plugs extending into the cylinders and adapted to enter the piston-rods and suitable connections between said hollow plugs and the exhaust-channels, substantially as described.

7. In apparatus of the character described, the combination with a suitable part, such for example as a cross-head, adapted to be connected with the door or device to be shifted, 15 of oppositely-arranged open-ended cylinders, pistons within said cylinders having piston-rods connected with said part or cross-head, a casing at the outer end of each of said cylinders provided with admission and exhaust 20 channels, a tubular rod connecting said casings, a valve for controlling the flow of fluid under pressure to and from said cylinders and a trigger for operating said valve, substantially as described.

25 8. In apparatus of the character described, the combination with a suitable part, such for example as a cross-head, adapted to be connected with the door or device to be shifted, of pistons on either side of and connected to 30 said part or cross-head, single-acting cylinders wherein said pistons are contained, admission and exhaust channels for delivering fluid under pressure to and from each of said cylinders, a valve-chamber provided with a 35 seat to which the admission and exhaust channels lead, a valve common to both of said cylinders for controlling the flow of fluid under pressure through said channels, and a valve-rod and means for shifting said rod to 40 operate said valve, substantially as described.

9. In apparatus of the character described, the combination with a suitable part, such for example as a cross-head, adapted to be connected with the door or device to be shifted, 45 of pistons connected to said part or cross-head, cylinders wherein said pistons are contained, admission and exhaust channels for delivering fluid under pressure to and from said cylinders, a valve-chamber provided with a seat 50 to which the admission and exhaust channels lead, a valve for controlling the flow of fluid under pressure through said channels, a valve-rod connected to said valve, a cylinder through which said valve-rod passes, said cylinder being connected by a suitable channel with the fluid-pressure supply and a piston within said cylinder connected to the valve-rod, substantially as described.

10. In apparatus of the character described, 60 the combination with a suitable part, such for example as a cross-head, adapted to be connected with the door or device to be shifted, of pistons on either side of and connected to said part or cross-head, single-acting cylinders wherein said pistons are contained, admission and exhaust channels for delivering fluid under pressure to and from said cylinders,

ders, a valve-chamber provided with a seat to which the admission and exhaust channels lead, a valve common to both of said cylinders 70 for controlling the flow of fluid under pressure through said channels, a valve-rod connected to said valve, a trigger attached to said valve-rod, suitable bearings for said valve-rod and suitable stops upon said rod, 75 substantially as described.

11. In apparatus of the character described, the combination with a suitable part, such for example as a cross-head, adapted to be connected with the door or device to be shifted, 80 of pistons connected to said part or cross-head, cylinders wherein said pistons are contained, a casing at the outer end of each of said cylinders provided with admission and exhaust channels for delivering fluid under pressure 85 to and from said cylinders, one of said casings being provided with a valve-chamber having a valve therein and a removable valve-seat attached to said casing, substantially as described. 90

12. In apparatus of the character described, the combination with a suitable part, such for example as a cross-head, adapted to be connected with the door or device to be shifted, of pistons connected to said part or cross-head, 95 hollow rods whereby said pistons are carried, cylinders wherein said pistons are contained, casings at the outer ends of said cylinders provided with admission and exhaust channels and hollow plugs extending through said 100 casings and adapted to enter said hollow piston-rods, said hollow plugs being provided with ports communicating with the exhaust channels, substantially as described.

13. In apparatus of the character described, 105 the combination with a cylinder and a piston therein adapted to operate a door or other device to be shifted, of channels for the admission and exhaust of fluid under pressure to and from said cylinder, a valve-chamber, a 110 valve therein for controlling the flow through said channels, and a valve-seat removably secured to said valve-chamber, said valve-seat having passages therein connecting said valve-chamber to said channels. 115

14. In a door-operating device, the combination of a cylinder, a piston therein for actuating a door or other device to be shifted, two ports opening into one end of said cylinder, means for closing one of said ports during the exhaust-stroke of the piston and an adjustable throttling-valve for the other of said ports, whereby the movement of the shifted part will be cushioned. 120

15. In a door-operating device, the combination of a cylinder, a piston therein for actuating a door or other device to be shifted, two ports opening into one end of said cylinder, outwardly-closing check-valve for one of said ports for closing the latter during the 130 exhaust-stroke, whereby the movement of the shifted part will be cushioned.

16. In a door-operating device, the combination with the cylinder and a piston therein

for actuating a door or other device to be shifted, of two ports opening into said cylinder through which the motor fluid escapes during the exhaust-stroke of said piston, one 5 of said ports arranged to be closed before the piston has completed its exhaust-stroke, whereby the movement of the shifted part will be cushioned.

17. In a door-operating device, the combination with the cylinder and a piston therein for actuating a door or other device to be shifted, of two ports opening into said cylinder through which the motor fluid escapes during the exhaust-stroke of said piston, one 10 of said ports opening into said cylinder intermediate its ends and arranged to be closed by the piston before it has completed its exhaust-stroke, the other of said ports opening into the end of the cylinder and an adjustable 15 throttling-valve for controlling the opening of said port, whereby the movement of the shifted part will be cushioned.

18. In a door-operating device, the combination with the cylinder and a piston therein for actuating a door or other device to be shifted, of two ports opening into said cylinder through which the motor fluid escapes during the exhaust-stroke of said piston, one 20 of said ports being mounted on the end of a tubular extension within said cylinder, a hollow 25 piston-rod for said piston into which said extension enters, the other of said ports opening into the end of said cylinder and provided with an adjustable throttling-valve, 30 whereby the movement of the shifted part will be cushioned.

19. In a shifting device for doors and the like, the combination with a cylinder and a piston therefor, of three ports opening into 35 one end of said cylinder, one of said ports provided with an outwardly-closing check-valve for closing the latter during the exhaust-stroke of the piston, means for closing another of said ports before the piston has completed 40 its exhaust-stroke, whereby the escape of the motor fluid during the last part of the exhaust-stroke will only take place through the remaining port.

20. In a shifting device for doors and the

like, the combination with duplicate cylinders and pistons therefor, of three ports opening into the outer ends of each of said cylinders, one of the ports of each of said cylinders being provided with an outwardly-closing check-valve for closing the latter during the 50 exhaust-stroke of the piston therein, another of said ports in each of said cylinders being located intermediate to ends thereof and arranged to be closed by the piston therein before it has completed its exhaust-stroke, and the remaining port in each cylinder being provided with an adjustable throttling-valve, whereby the movement of the part to be shifted in each direction will be cushioned.

21. In a shifting device for doors and the like, the combination with duplicate, single-acting cylinders and pistons therein rigidly connected together by a common hollow piston-rod, of three ports opening into the outer 60 ends of each of said cylinders, one of the ports 65 in each cylinder being provided with an outwardly-closing check-valve, another of said ports being mounted upon the inner end of tubular extensions within said cylinders, said extensions being adapted to enter said hollow 70 piston-rod, and the remaining ports in each cylinder being provided with an adjustable throttling-valve, whereby the movement of the part to be shifted in both directions will be cushioned.

22. In a shifting device for doors and the like, the combination with a cylinder and a piston therein, a valve-chamber, a valve therein controlling the admission and exhaust of fluid under pressure to and from said cylinder, a valve-rod therefor, a chamber surrounding said rod, and a piston within said chamber secured to said rod, there being an opening leading from said valve-chamber to said piston-chamber, whereby the valve is automatically operated in one direction by the fluid-pressure.
